DESIGN FOR A PUTTING GAME APPARATUS

Fred W. Preece, Toledo, Ohio

Application October 6, 1937, Serial No. 72,029

Term of patent 3½ years

To all whom it may concern:

Be it known that I, Fred W. Preece, a citizen of the United States, residing at the city of Toledo, in the county of Lucas and State of Ohio, have invented a new, original, and ornamental Design for a Putting Game Apparatus, of which the following is a specification, reference being had to the accompanying drawings, forming a part thereof.

Fig. 1 is a side perspective view of a putting game apparatus embodying my new design, and Fig. 2 is a front perspective view of the same.

I claim:

The ornamental design for a putting game apparatus, as shown.

FRED W. PREECE.
